UNITED STATES PATENT OFFICE.

FRANK W. WOLFF, OF PARNASSUS, PENNSYLVANIA, ASSIGNOR TO P. H. MURPHY COMPANY, OF PARNASSUS, PENNSYLVANIA, A CORPORATION OF PENNSYLVANIA.

CAR-ROOF.

1,280,350.

Specification of Letters Patent.

Patented Oct. 1, 1918.

Application filed July 8, 1918. Serial No. 243,768.

To all whom it may concern:

Be it known that I, FRANK W. WOLFF, a citizen of the United States, and a resident of Parnassus, county of Westmoreland, and 5 State of Pennsylvania, have invented a new and useful Improvement in Car-Roofs, of which the following is a specification.

My invention relates to car roofs and more particularly to outside metal car roofs 10 comprising a plurality of metal sheets movably mounted on the substructure. One of the principal objects of the invention is to enable such roofs to accommodate the various distortions arising from the racking 15 and weaving of the car and avoid buckling the roof sheets.

The invention consists in a roof sheet especially adapted for use at the ends of a car roof, and in the weatherproofing means for 20 its outer margins. The invention further consists in the parts and combinations of parts hereinafter described and shown.

In the accompanying drawings which form part of this specification and wherein 25 like symbols refer to like parts wherever they occur,

Figure 1 is a plan view of an end portion of a car roof showing my invention applied thereto;

Fig. 2 is an end elevation of the upper portion of the car shown in Fig. 1;

Fig. 3 is a plan view similar to Fig. 1, the end sheet caps being removed, one of the roof sheets being broken away so as to disclose the eaves and end flashings;

Fig. 4 is an enlarged vertical longitudinal section through the hood casting at the ridge on the line 4—4 in Fig. 2;

Fig. 5 is a detail end view of the end portion of the car at the ridge, the hood casting being shown in section on the line 5—5 in Fig. 4;

Fig. 6 is a plan view of the end portion of the car at the ridge, the portion of the hood casting overlying the ridge ends of the end sheet cap being broken away;

Fig. 7 is a vertical cross-section through the end portion of the car near the ridge line on the line 7—7 in Fig. 1;

Fig. 8 is a vertical cross-section taken through the end portion of the car adjacent the eaves on the line 8—8 in Fig. 1; and

Fig. 9 is a vertical cross-section through the eaves portion of the car on the line 9—9 in Fig. 1 showing a means for loosely secur-

ing the eaves ends of the roof sheets to the roof substructure.

The roof shown in the drawings comprises a wooden substructure consisting of roof sheathing boards 10 supported at their 60 end on a side plate 11, one end only of the car being shown. Metal roof sheets 12 rest on the roof sheathing boards 10 and extend transversely of the car from eaves to ridge. The ridge ends of abutting sheets are connected by standing seams 13. The sides of adjacent sheets are connected by standing 65 seams 14. The endmost roof sheets are cut obliquely or on the bias, the ridge end of each sheet being wider at the ridge than at 70 the eaves.

Eaves flashings 15 of angle section rest in shallow grooves along the eaves edge of the car, their end portions being turned down over the eaves edge of the roof sheathing 75 and nailed to fascia board 16. The eaves flashings 15 have rebent portions 17 interlocking with the doubled under ends 18 of the roof sheets 12.

End flashings 19 of angle section, similar 80 to the eaves flashings, lie in grooves along the tops of the ends of the car. The vertical down-turned portion of the end flashing is secured to the end fascia 20 of the car in a manner similar to the eaves flashings 15. 85 The inner marginal portions 21 of the end flashings are doubled back substantially flush with the under sides of the endmost roof sheets. The outer marginal portions of the endmost sheets project beyond the 90 doubled back portions 21 of the end flashings 19. Metal caps 22 of angle section are arranged on each side of the ridge seam, their horizontal portions overlapping the outside marginal portions of the end sheets. 95 The vertical portions of the cap overhang the end of the car and are secured to the end fascia 20 by nails 23. The horizontal portions of the caps 22 which overlap the end flashing and the side marginal portions of 100 the end sheets are wider at the eaves than at the ridge. The inner margins 24 of the horizontal portions of the caps are turned under and bear against the roof sheets. The vertical portions of the caps have corruga- 105 tions 25 which stiffen them. These corrugations extend a short distance over the horizontal portions of the caps. The inner margins of the horizontal portions of the caps are flat to minimize the danger of water and 110

- dirt finding their way into the car. A hood cap 26 is preferably secured to the end fascia 19 by nails 27, the hood portion of which straddles the open end of the ridge seam 5 and also covers the meeting ends of the end sheet caps. The unavoidable relative movement between the roof sheets and the sub-structure, such as the diagonal movement of the roof sheets when the car is thrown out 10 of square results in a greater amount of movement of the roof sheets at the eaves than at the ridge. This movement is accommodated without decreasing the weather-proofing qualities of the roof by the wide 15 overlap of the end sheet and end sheet cap at the eaves of the car. The cutting of the end sheets and the end sheet caps on the bias decreases the amount of material needed for these members.
- 20 The end sheet cap shown is adapted for use with other styles of roof than the one described. It is evident that changes may be made without departing from the invention and I do not wish to be limited to the construction shown.
- 25 What I claim is:
1. In a car roof, an end sheet wider at the ridge than at the eaves and a cap for said end sheet, said cap overlapping said end sheet and being wider at the eaves than at the ridge.
  2. In a car roof, an end sheet movably mounted on the substructure, a cap for said end sheet, said cap being secured to the car and having a portion overlapping said end sheet, the margins of the lapping portions of the end sheet and cap being cut obliquely, whereby the lap between said end sheet and cap is greatest at the eaves of the car.
  3. In a car roof, a movably mounted end sheet, and a cap for said end sheet, said cap having a portion adapted to overlap the side outer margin of said sheet, the lap between the end sheet and cap being greater at the eaves than at the ridge of the car.
  4. In a car roof, end roof sheets movably mounted on the substructure on each side of the ridge line of the car, said sheets being connected by seams at the ridge, and a cap secured to the car, a portion of said cap overlapping the outside margin of the end roof sheets, the side margin of said end roof sheets adjacent to the end of the car being closer to the end of the car at the ridge than at the eaves.
  5. In a car roof, an end sheet having its marginal portion adjacent to the car end stopping short thereof, and a cap secured to said car, said cap having a portion adapted 60 to cover said marginal portion of said roof sheet, said marginal portion of the end sheet

being cut obliquely on each side of the ridge whereby said marginal portion is farther from the end of the car at the eaves than at the ridge.

65

6. In a car roof, an end roof sheet, the marginal portion of said roof sheet adjacent the end of the car being cut diagonally at opposite angles on each side of the ridge, and a cap secured to the car having a portion 70 overhanging the marginal portion of said end sheet and the marginal portion of the overhanging portion of the cap being cut diagonally at opposite angles on each side of the ridge, the angle of the marginal 75 portion of the cap being greater than the angle of the marginal portion of the end sheet at each side of the ridge.

70

7. In a car roof, an end sheet, the marginal portion of said sheet adjacent the 80 ridge of the car being cut diagonally from the ridge to the eaves away from the end of the car, and a cap secured to the car, said cap overlapping the diagonally cut marginal portion of the end sheet, whereby the capacity 85 for relative movement between the end sheet and the cap is greater at the eaves than at the ridge.

80

8. In a car roof the combination with end roof sheets connected by ridge seams and 90 arranged on each side of the ridge, a flashing member secured to said car beneath the end roof sheets, caps for covering the marginal portions of the end roof sheets adjacent to the end of the car, said caps being 95 secured to the end of the car at each side of the ridge seam, a hood cap secured to the car having a hood portion covering the end of the ridge seam and the adjacent ridge ends of the caps, the end sheets being wider at 100 the ridge than at the eaves and the end sheet caps being wider at their eaves than at the ridge.

100

9. A car roof, roof sheets movably mounted thereon on opposite sides of the ridge and 105 connected along the ridge by seams, spaced end caps overlapping the side outer margins of the endmost sheets, said end caps being arranged on each side of the ridge seam, hood caps for covering the ridge seam of 110 the endmost sheets and the spaced ridge ends of the end sheet caps, the side outer marginal portion of the endmost sheets and the overlapping portions of the end sheet caps being cut obliquely from the ridge to the eaves, 115 whereby the overlap between the side outer marginal portion of the end sheets and the end caps is greater at the eaves than at the ridge.

115

Signed at Parnassus, Pa., this 1st day of 120 July, 1918.

FRANK W. WOLFF.
